DESIGN FOR A PULL TAB FOR SLIDE FASTENERS

Alex Walker, New York, N. Y.

Application August 12, 1935, Serial No. 58,095

Term of patent 3½ years

To all whom it may concern:

Be it known that I, Alex Walker, a citizen of the United States, residing at 156 East 37th Street, city, county, and State of New York, have invented a new, original, and ornamental Design for a Pull Tab for Slide Fasteners, of which the following is a specification, reference being had to the accompanying drawing, forming a part thereof.

Fig. 1 is a front elevation of the pull tab, as attached to the slider.

Fig. 2 is an end view of the pull tab, as attached to the slider.

The dominant feature of the design is the contour of the pull tab.

I claim:

The ornamental design for a pull tab for slide fasteners as shown and described.

ALEX WALKER.
